Des. 179,748
Patented Feb. 19, 1957

179,748

BOARDING LADDER

Charles W. Tunstead, Minneapolis, Minn.

Application December 30, 1955, Serial No. 39,539

Term of patent 14 years

(Cl. D15—8)

Figure 1 is a front perspective view of a boarding ladder, showing my new design; and

Figure 2 is a rear perspective view of the same.

I claim:

The ornamental design for a boarding ladder, substantially as shown.
